UNITED STATES PATENT OFFICE.

WILLIAM JACOB KURTZ, OF MCKEESPORT, PENNSYLVANIA.

ROD-BENDING MACHINE.

SPECIFICATION forming part of Letters Patent No. 775,774, dated November 22, 1904.

Application filed March 1, 1904. Serial No. 196,000. (No model.)

To all whom it may concern:

Be it known that I, WILLIAM JACOB KURTZ, a citizen of the United States of America, residing at McKeesport, in the county of Allegheny 5 and State of Pennsylvania, have invented certain new and useful Improvements in Rod-Bending Machines, of which the following is a specification, reference being had therein to the accompanying drawings.

10 This invention has relation to machines for making molders' gагgers, and has for its object the provision of means whereby gагgers, which are small pieces of bent metal used by molders to assist in holding the sand in place, 15 in the mold, may be rapidly and perfectly formed from metal rods at a speed far in excess of the present method of manufacturing these articles and at greatly-reduced cost. The present practice is to form the gагgers from 20 metallic rods of suitable size by hand, the rod being bent twice at right angles, the bends being made a distance apart depending upon the length of the gагger which it is desired to produce. This procedure is slow, laborious, and 25 expensive, and I propose to provide means whereby the services of the skilled workman required in making these articles may be dispensed with, the quantity produced by a workman in a given time may be increased, and 30 the cost reduced to a minimum, while at the same time the articles produced will be more regular in form and of more exact length than the hand-made articles.

Having the above object in view, I have devised the mechanisms hereinafter described and claimed, and illustrated in the accompanying drawings, and constituting my invention.

In the said drawings, Figure 1 is a side elevation of my improved machine for making 40 gагgers. Fig. 2 is a vertical sectional view of the same. Fig. 3 is a detail view in plan and elevation of one of the parts of the machine. Fig. 4 is a front view of the machine shown in Fig. 1. Fig. 5 is a side view of part 45 of the framing of the machine and of part of the gaging devices of the machine. Fig. 6 is an end view of the parts shown in Fig. 5.

The frame of the machine is composed of two upright standards 12, suitably supported 50 on a base 3, to which the standards are at-

tached by angle-braces 44. Brackets 55 are attached to the angle-braces 44 and to the standards 12 and support between them a table 6, having a downwardly-inclined extension 7, an anvil-block 8 being mounted between the standards, with its lower edge on alignment with the top of the table 6. The standards 12 are formed with vertical ways 9, and a vertically-movable rack-bar 10 is arranged between the standards and slides on the said ways. The rack-bar 10 is pierced at its lower end, as shown at 11, and a cutter-jaw 12, formed with an orifice 13, coinciding with the hole 11 in the rack-bar, is fixed in position between the standards 12, so that the lower 60 end of the rack-bar and the said cutter-jaw constitute shears adapted to sever a rod passing through the holes 11 and 13 when the rack-bar is moved longitudinally. The cutter-jaw 12 is adjustably mounted in the standards, being held in position by horizontal bolts 14, that pass through holes 15 in the standards, a row of these holes being formed in each standard and extending from above the anvil-block to a point near the tops of the standards. 75

Brackets 16 extend outwardly in front of the standards, and in the brackets 16 is pivotally supported, by means of a bolt 17, a swinging arm 18, which carries on its lower end a triangular block 19, having its lower 80 side 20 at right angles to said arm 18. Brackets 21 project from the standards 12 below the brackets 16, these brackets being provided for the attachment of an arm 22, which carries a triangular block 23 at its lower end, 85 this arm and block being shown in detail in Fig. 3 and being identical in construction with the arm 18 and the block 19 except that the arm 22 is shorter than the arm 18, the arm 22 and its block 23 being adapted to be substituted for the arm 18 and block 19 when certain sizes of gагgers are to be made in the machine, as will be hereinafter described. 90

Brackets 24, which may be made integral with the brackets 16, serve as journals for a 95 shaft 25, upon which is loosely mounted a gear-wheel 26, that meshes with the rack-bar 10, and the said shaft 25 serves also as a pivot for a bent lever 27, which is formed with bifurcated arms 28, that embrace the gear- 100

wheel 26, said levers being connected to arm 18 by a link 18'. A toothed block 29 is slidably mounted between the bifurcated arms 28 of lever 27, being supported and guided by pins 30 passing through the block and bearing on the top and bottom of each bifurcated arm. A rod 31 is pivotally secured to ears 32 on the back of the block 29 and at its other end is pivotally secured to a rocking lever 33, pivoted at 34 to the lever 27. Upon that end of the rocking lever to which the rod 31 is attached an eye 35 is formed that receives one end of a spiral spring 36, the opposite end of which is secured to the lever 27, and to the opposite end of said rocking lever 33 a rod 38 is attached, the other end of said rod 38 being attached to a bell-crank lever 39, which is pivoted at 40 to the lever 27, the free end of said bell-crank lever constituting a handle or grip by means of which through the rod 38, the rocking lever 33, and the rod 31 the toothed block 29 may be pressed into engagement with the gear-wheel 26, the said block 29 being moved out of engagement with the gear-wheel when the grip or handle 41 is released by the spring 36.

Upon the outside of the standard 2 is pivotally mounted a sleeve 42, said sleeve being pivoted at 43 to the standard and formed with a rearwardly-projecting arm 44, to which is attached one end of a spiral spring 45, the other end of which is attached to the standard 2, the said spring serving to maintain the sleeve normally in a horizontal position and a stop 46 serving to limit the movement of the sleeve, so that it will not pass such horizontal position under the pull of the spring. A gage-rod 47 passes through the sleeve 42 and is held at any position to which it may be adjusted in the sleeve by a set-screw 48'. The outer end of a gage-rod 47 carries a gage-plate 48, the said gage-plate being disposed at right angles to the gage-rod 47 and projecting upwardly above the same and being formed with a guide-plate 49 on one of its ends, which is engaged by a pin 50, projecting laterally from the upper corner of the triangular block 19 on the swinging arm 18.

The machine being constructed as above described and shown in the accompanying drawings is operated in the following manner: A rod 51 of the proper size for the formation of the gagger is passed through the hole 11 in the bottom of the rack-bar 10 and through the hole 13 in the cutter-jaw 12 and pushed forward until it contacts with the gage-plate 48, which has been previously adjusted to the position necessary to secure the length of gagger desired, the holes 13 and 11 being in alinement at this time. The lever 27 is now drawn down and the swinging arm 18 depressed and gradually brought to the position shown in Fig. 1 of the drawings in dotted lines. During the first part of the movement of the swinging arm 18 the pin 50 on the tri-

angular block 19 will contact with and ride against the edge of the guide-plate 49 and eventually contacting with the rod 47 will depress the rod and the gage-plate, so as to carry the same downwardly beneath the table 70 67. The lower corner of the swinging arm 18 will at the first movement of the swinging arm contact with the outer end of the rod 51 and will bend the rod downwardly, the latter bending over the outer edge of the hole 13 in 75 the cutter-block 12, and this bending of the rod will continue during the entire movement of the arm 18, finally resulting in the rod 51 being bent downwardly in alinement with the front of the standards, and consequently at 80 a right angle to that portion of the rod which remains outside the hole 11 in the sliding rack 10. As soon as the outer end of the rod 51 reaches the inclined portion 7 of the table 6 it begins to bend outwardly, and the continuation of the movement of the swinging arm 18 results in the end of the rod being bent at a right angle to the portion which is in alinement with the standards between the table 6 and the face 20 of the triangular block 85 19. Just previously to the completion of the right-angular bend of the rod 51 the grip or handle 41 is pressed toward the lever 27. This movement of handle 41 forces the toothed block 29 into engagement with the gear-wheel 90 26, and the latter now turning with the lever 27 elevates the rack-bar 10 and shears off the bar 51 at the juncture of the holes 11 and 13, this shearing off of the bar occurring substantially at the same moment as the completion of the bending of the bar 51, and the bent section thus cut off from the bar 51 constituting the complete gagger. The lever 27 is now raised to its elevated position, the handle or grip 41 being released, so that the spring 100 36 will pull the toothed block 29 out of engagement with the gear-wheel 26, whereupon the gear-wheel being loose on its shaft will turn freely and permit the rack-bar 10 to drop and bring the hole 11 therein again into alinement with the hole 13 in the cutter-jaw 12. Meanwhile by the upward movement of the swinging arm 18 the gage-rod 47 is allowed to move upwardly and will eventually resume its position in alinement with the holes 115 in the cutter-jaw and the rack-bar. The downward movement of the rack-bar 10 is limited by the lowermost tooth of its rack, which comes into contact with the upper surface of the cutter-jaw 12. 120

When the swinging arm 18 is employed in connection with the machine, the cutter-jaw 12 is located in the position shown in the drawings; but when the swinging arm 22 is to be used the cutter-jaw is adjusted to a position 125 below the bracket 21, in which said swinging arm 22 is pivoted, this substitution and adjustment of parts being done when it is desired to make gagger having short body portions, and it will be understood that with the 130

short swinging arm 22 the cutter-jaw 12 can be lowered to any point between the bracket 21 and the top of the anvil 8. When the shorter swinging arm 22 is used, the gage-bar 47 is 5 adjusted in the sleeve 42, so that the gage-plate will be in proper position for engagement with the projecting arm on the side of the triangular block 23 and will properly gage the length of rod appropriate for the formation 10 of the desired size of gagger.

Having fully described my invention, I claim—

1. In a machine for forming gaggers, the combination of a cutter-jaw, a swinging arm, a 15 stationary table, a sliding rack-bar, adapted to move past said cutter-jaw and constituting in connection therewith shears, with means for moving said swinging jaw and means for moving said rack-bar, substantially as described.
2. In a machine of the type described, the combination of a supporting-frame, a swinging gage carried on said frame, a swinging arm adapted to move said gage, a cutter-jaw 20 mounted in the framing of the machine, a sliding bar adapted to operate in conjunction with said cutter-jaw to sever a rod passing between the cutting edges of said bar and said jaw, means for moving said swinging arm to bend a rod arranged to be cut by the sliding 25 bar, and means carried by the moving means of the swinging arm for moving said bar relatively to the cutter-jaw.
3. In a machine of the type described, the combination of vertical standards, a table 30 mounted in proximity to said standards, an anvil mounted on the standards, a cutter-jaw

mounted on the standards, a sliding rack-bar having a cutter edge adapted to coat with the cutting edge of said cutter-jaw, a lever pivotally mounted on the standards, a gear-wheel journaled on the standards and meshing with said rack-bar, a lever pivoted on the standards, a sliding member mounted on said lever and adapted to engage said gear-wheel, means for moving said member into and out 45 of engagement with said gear-wheel, a swinging arm journaled on the standards and connected to said lever, and a movable gage adapted to be moved into and out of alignment of said cutter-jaw by the movement of said lever. 50

4. In a machine of the type described, the combination with supporting-standards of adjustable cutting means mounted thereon, a swinging arm, a lever for swinging said arm, and for operating said cutting means, a stationary table over which said arm is adapted to swing, said arm being adapted to bend a section of metal between the said standards and the said table. 55

5. In a machine of the type set forth, gage 60 means, bending means in engagement therewith, cutting devices operated by said bending means, said bending means arranged to move the gage means therewith, and means for returning the gage means to its normal position simultaneously with the bending means. 65

In testimony whereof I affix my signature in the presence of two witnesses.

WILLIAM JACOB KURTZ.
